UNITED STATES PATENT OFFICE.

DEL ROY F. FOWLER, OF MELROSE PARK, PENNSYLVANIA.

TOOL FOR FILLING UPHOLSTERY POCKETS.

Application filed April 28, 1925. Serial No. 26,394.

To all whom it may concern:

Be it known that I, DEL ROY F. FOWLER, a citizen of the United States of America, and resident of Melrose Park, county of 5 Montgomery, State of Pennsylvania, have invented a certain new and useful Improvement in Tools for Filling Upholstery Pockets, of which the following is a true and exact description, reference being had 10 to the accompanying drawings, which form a part thereof.

My invention relates to the construction of tools by means of which a bat of filling material such as cotton is inserted in pockets 15 or pleats in, for instance, automobile upholstery.

The object of my invention is to provide a tool through which the bat can pass freely, by means of which the bat can be tightly 20 gripped particularly at the front end of the tool and which tool can be opened out to give access to the bat lying within it.

The nature of my invention will be best understood as described in connection with 25 the drawings which illustrate a tool having my improvements and in which

Figure 1 is a plan view of my tool.

Figure 2, a plan in central horizontal section showing the bat in place.

30 Figure 3 is a cross section on line 3—3 of Fig. 1.

Figure 4, a cross section on line 4—4 of Fig. 1.

Figure 5 is a plan view showing the 35 trough members spread apart.

Figure 6 is a perspective view showing the tool in use, and

Figure 7 is a vertical longitudinal section showing a modification.

40 A, A' is the tubular base of the tool, that part A having a funnel shape and the part A' having an elliptical section with parallel walls. B and B' are metal tongues fastened to the bottom and top of the A' section of the base and extending, as shown in 45 Figs. 1, 2 and 5, for the full length of the tool. By preference, the lateral sides of the tongues angle to each other, as indicated at b b Fig. 3. C, C, are trough shaped sections of the tool, the edges of which preferably angle towards each other, as indicated at C', C', Fig. 3. The sections C, C, are pivotally attached to the base section A' as by rivets D, D, and so as to turn freely 50 from, for instance, such a position as is

shown in Fig. 5, to a position such as is shown in Fig. 2. As shown in Figs. 1, 2 and 5, the members B, B' and C, C, are of the same length so that their terminal edges C², C², B², B², register together, as shown 60 in Figs. 1 and 2. In the modification of Fig. 7, the upper tongue B' only extends to the point B³.

The trough shaped sections C, C, are so shaped and so pivotally attached to the tubular base that they do not in use overlap each other and form a complete container for the bat, but they do overlap the edges of the top and bottom tongues B', B, and preferably in such manner that the angling 70 edges C' of the sections C contact with the edges b of the tongues at the outer end of the tool so as to press the tongues B, B', inward against the bat when the trough sections are moved together.

E indicates the bat of filling material. E' the end of the bat projecting beyond the end of the tool. F is the upholstery container formed into pleats or pockets F', F'.

In operation the bat E is introduced into 80 the tool so that an end E' will extend for a short distance beyond it and as shown in Fig. 2. The operator then grasps the pivoted trough shape sections, pressing them together over the edges of the tongues B, B', and pressing the tongues inward on the bat which at the end of the tool is thus 85 lightly gripped and compressed but left with a projecting portion E'. The tool thus charged is inserted in a pocket F and forced back to the end thereof so that the end E' of the bat is compacted against the end of the pocket. The operator then relaxes his grip on the sections C, C, and after grasping the free end E' of the bat through the 90 end of the pocket F he withdraws the tool leaving the bat in the pocket and at the same time recharging the tool with a fresh portion of the bat. The bat is, of course, severed so as to leave a charge in the pocket 95 100 and a projecting end E' on the new charge of the tool.

The modified tool of Fig. 7, in which the tongue B' does not extend to the end of the tool, does not beyond the end B³ completely 105 enclose the bat and in the case of this tool the top portion E² of the bat will, when the charged tool is inserted in a pocket and the grip on its members is relaxed, bulge up against the fabric of the pocket and by fric- 110

tion therewith assist in holding the bat in the pocket while the tool is being withdrawn.

Having now described my invention, 5 what I claim as new and desire to secure by Letters Patent, is:

1. A tool for filling upholstery pockets comprising a tubular base, non-overlapping trough shaped sections pivotally attached 10 to said base at one end so as to swing towards or away from each other and tongue sections attached to the base and extending below and between the edges of the trough

shaped sections to form with said trough shaped sections an enclosure for the bat of 15 stuffing material when the trough shaped sections are moved together.

2. A tool having the features of claim 1, further characterized by having the ends of the trough shaped sections and at least one 20 of the tongue sections located at the same distance from the base and adapted to form smooth gripping edges at the end of the tool.

DEL ROY F. FOWLER.
